UNITED STATES PATENT OFFICE.

WILLIAM S. TIDSWELL, OF LANSING, MICHIGAN.

SPRINKLER.

1,139,086.

Specification of Letters Patent. Patented May 11, 1915.

Application filed October 16, 1914. Serial No. 866,984.

To all whom it may concern:

Be it known that I, WILLIAM S. TIDSWELL, a citizen of the United States of America, residing at Lansing, in the county of Ingham 5 and State of Michigan, have invented certain new and useful Improvements in Sprinklers, of which the following is a specification, reference being had therein to the accompanying drawings.

- 10 My invention relates to sprinklers and has among the objects thereof to provide a construction of sprinkler that will discharge the water therefrom in a fine spray which is so directed as to fall within a restricted 15 area on both sides of the sprinkler; further, to provide a sprinkler which not only is adapted to be used for lawns but which is so constructed that it may be employed for spraying trees, bushes or the like.
- 20 The invention further has among the objects thereof to provide a device that may be easily and cheaply manufactured.

Other objects of the invention will more fully hereinafter appear.

25 The invention resides in the peculiar construction, arrangement and combination of parts as hereinafter set forth.

In the drawings, Figure 1 is a perspective view of the device embodying the invention; 30 Fig. 2 is a longitudinal section thereof; Fig. 3 is a section on the line $x-x$ of Fig. 2; and Fig. 4 illustrates a modification.

My improved sprinkler comprises sides A and B and a bottom C; the sides and bottom 35 preferably being flat and formed from a single piece of metal. The upper edges of the sides are substantially semicircular in shape, as indicated in Fig. 2, and secured to the upper edges of the sides is a flat strip D provided with a plurality of perforations. 40 This strip closes the upper edges of the sides and has its ends secured to the ends of the bottom. Preferably there are two rows of perforations E and F, the rows being arranged adjacent the sides A and B while 45 the members of one row are arranged in staggered relation to the members of the

other row, which will be readily apparent upon reference to Fig. 1. The perforations are comparatively small, preferably being 50 about 1/100 of an inch in size and therefore the water discharged from the apertures or perforations is in the form of a fine spray, while by staggering the perforations one row in relation to those of another, it is 55 found that the stream discharged from the sprinkler not only is in the form of a mist or very fine spray but also is comparatively uniform.

Secured to one of the sides as A is a 60 coupling G for engaging a hose or the like. If desired a deflector may be employed which extends upwardly from the bottom at an angle to the walls A and B, which will tend to break the force of the water entering the 65 sprinkler.

Because of the shape of the sprinkler the stream discharged therefrom will be restricted in area, which allows the sprinkler not only to be set close to sidewalks or the 70 like but also permits the sprinkler to be attached to a spray-pole for spraying trees, bushes or the like.

My improved construction of sprinkler is one which not only is very desirable since 75 it throws a very fine spray, but also the sprinkler is simple in construction and may be easily and cheaply manufactured.

What I claim as my invention is:—

A sprinkler, comprising a comparatively 80 flat base and upwardly-extending sides having similarly arched upper edges, of a perforated strip secured to said edges forming the sprinkler top, a coupling connected to one of the sides, and a deflector within the 85 sprinkler extending upwardly from the base at an angle to the side walls.

In testimony whereof I affix my signature in presence of two witnesses.

WILLIAM S. TIDSWELL.
